UNITED STATES PATENT OFFICE.

SAMUEL E. SNYDER, OF BROOKLYN, NEW YORK.

WINDOW SHADE.

Application filed April 17, 1922. Serial No. 552,604.

To all whom it may concern:

Be it known that I, SAMUEL E. SNYDER, a citizen of the United States, residing in the borough of Brooklyn, county of Kings, city 5 and State of New York, have invented an Improvement in Window Shades, of which the following is a specification.

The present invention relates to window shades and has for an object to provide an 10 improved arrangement whereby a shade of adjustable length may be supported at any desired height relative to the top or bottom of the window opening.

The invention provides means for supporting a spring roller and its attached shade in inverted position, the shade being supported by its free end in such manner that its elevation may be adjusted to cover any desired portion of the window opening.

20 The nature and objects of the invention will be better understood from a consideration of an illustrative embodiment of the invention. For the purposes of such description reference will be had to the accompanying 25 drawing forming a part hereof, wherein

Figure 1 is a front elevation of a window shade arrangement constructed in accordance with and embodying the principles of the invention and shown as applied to a 30 window opening;

Figure 2 is a detail view of the side elevation showing the depending frame 5, and

Figures 3 and 4 are sectional views of the 35 spring rollers used with the invention, showing their associated pawls.

In the arrangement shown for the purpose of illustrating the invention, a shade 1 with its spring roller 2 is shown as supported in inverted position, the supporting means being 40 attached for convenience to the filler stick 3. In this arrangement the roller, which may be of usual construction and provided with pawls 2', serves as a weight to maintain the shade taut and to prevent its being easily 45 blown from position by drafts of air. Suitable means is provided for maintaining the roller in adjusted position and preventing the accidental unrolling of the shade. The means shown comprises a frame 5 which engages and is supported by the two trunnions of the shade, the non-rotatable trunnion 6 being held against rotation by fitting a correspondingly shaped slot 7 in the frame. The frame 5 and its connected parts are 50 preferably made of sufficient weight and the weight is so distributed that the same

will hang vertically beneath the roller. As shown, the frame is offset from the line of the trunnions so that it hangs in line with the shade which supports it, as shown in 55 Figure 2. The frame is preferably of a width equal to the width of the shade 1, the ears which engage the roller trunnions being offset outwardly as shown. If the weight of the frame is insufficient a weight 10 may 60 be secured to or form a part of the frame. This weight and the frame are preferably covered with suitable material 11 so that the frame with its covering constitutes a shade section of fixed length and of a width 65 equal to the width of the shade 1.

The means for supporting the shade, spring roller, and the weighted frame, is 70 preferably arranged to sustain the shade at any desired elevation in the window opening. In this way the shade may be arranged to cover any desired portion of the window opening. A cord 25 is secured to and depends from the filler stick 3, and a cord 26 is 75 secured to and depends from the weight 11. The spring 22 is so formed as to be a trifle 80 stronger in tension than the spring in the roller 2, and it will be obvious that should it be desired to raise the shade 1 without changing the position of the spring roller 2 it is only necessary to hold the cord 26 and 85 then pull downwardly on the cord 25 whereupon the pawls in the spring roller 15 are 90 released, as is usual in spring rollers, whereupon the shade 1 would be raised (and unrolled from the spring roller 2), to the desired elevation, through the medium of the cords 14, which latter would be wound on the cones 21 in an obvious manner. As 95 shown, suitable tension members, as cords, 14, 14 are secured to the opposite ends of the filler stick 3 and extend over and are 100 attached to a spring roller 15 mounted in the window frame 16 at the top thereof. This spring roller is, in general, of usual 105 construction, having at one end a rotatable trunnion mounted in a suitable bracket 17 and at its opposite end a non-rotatable trunnion 18 non-rotatably mounted in a suitable bracket 19, the roller being provided with 110 the usual gravity pawls 15' to hold it in adjusted position. The supporting cords 14, 14 are preferably arranged to wind onto conical sections 20 of the spring roller 15, the arrangement being such that when the 115 shade is raised to the top of the window and the spring of the spring roller 15 is in rela-

tively unwound condition the cords engage the roller at the smaller portion of the cones and therefore nearer the axis of the roller, whereas when the shade is down near the bottom of the window, in which condition the spring of the roller 15 is in relatively wound-up condition and therefore under greater tension, the cords engage near the larger end of the cones, having a greater leverage. By this arrangement the increased tension of the spring of the roller when the shade is in its lowermost position is substantially equalized by the greater leverage of the pull of the cord on the outer diameter of the cones.

As shown, the cone sections are made separate and grooves 21 are formed to guide the cords 14, 14 in winding and unwinding. In order that the cones may be of as small diameter as possible at the smaller end, the spring 22 of the roller is secured to the usual center rod 23 at a point spaced from the end of the roller, and the adjacent cone section 20 is made to substantially fit this center rod.

Various possible embodiments may be made of the invention and various changes in the embodiment described may be made, all within the scope of the subjoined claims,

I claim as my invention:

1. The combination with a shade of a spring roller having conical sections, tension members each connected at one end to the roller and wound on the conical sections and connected at their other ends to the shade, whereby as the tension members are unwound and the spring of the spring roller is wound tighter the tension members act on a larger diameter of the roller.
2. The combination with a spring roller and its attached shade, of a second spring

roller having conical sections, tension members each connected at one end to the first mentioned roller and at their other ends to said second mentioned roller and adapted to be wound on the conical sections whereby as the tension members are unwound and the spring of the spring roller wound tighter the tension members act on a larger diameter of the roller, and means secured to said first mentioned roller for maintaining the same in any desired vertical position.

3. The combination with a shade and its roller of adjustable means for supporting the same in desired position, comprising a spring roller having conical grooved sections and cords arranged to wind in said grooved sections, whereby as said cords are unwound the spring of said roller is wound tighter and said cords act on a larger diameter of the roller.

4. The combination with a shade and its spring roller, a second spring roller rotatably mounted at the top of a window opening or the like, and provided with conical end sections, cords secured to said shade and to said conical sections and so arranged that upon rotation of said second spring roller and consequent increased tension of the spring thereof said cords act on a larger diameter of said conical sections whereby tension of the spring of the roller is equalized by the cords, a frame engaging the trunnions of said first mentioned spring roller and depending therefrom and arranged to prevent rotation of said roller.

In testimony whereof, I have signed my name to this specification this 10th day of April, 1922.

SAMUEL E. SNYDER.
